CLAIM

We claim the ornamental design for an oral care device, as shown and described.

DESCRIPTION

FIG. 1 is a front, right, perspective view of the claimed design of the oral care device, according to an embodiment; FIG. 2 is a rear, right, perspective view of the claimed design of FIG. 1; FIG. 3 is a top view of the claimed design of FIG. 1; FIG. 4 is a bottom view of the claimed design of FIG. 1; FIG. 5 is a left side view of the claimed design of FIG. 1; FIG. 6 is a right side view of the claimed design of FIG. 1; FIG. 7 is a front side view of the claimed design of FIG. 1; and, FIG. 8 is a rear side view of the claimed design of FIG. 1. The ornamental design which is claimed is shown in solid lines in the drawings. The broken lines in the drawings are for illustrative purposes only and form no part of the claimed design. Oblique lines show a transparent, reflective, or shiny surface, and not surface ornamentation.
